(57) **CLAIM**

The ornamental design for a gas valve with integrated pressure regulator, as shown and described.

DESCRIPTION

FIG. 1 is a downward front perspective view of the design for a gas valve with integrated pressure regulator; FIG. 2 is a further downward front perspective view thereof; FIG. 3 is a downward rear perspective view thereof; FIG. 4 is a further downward rear perspective view thereof; FIG. 5 is an upward front perspective view thereof; FIG. 6 is a further upward front perspective view thereof; FIG. 7 an upward rear perspective view thereof; FIG. 8 is a further upward rear perspective view thereof; FIG. 9 is a front elevational view thereof; FIG. 10 is a rear elevational view thereof; FIG. 11 is a left side elevational view thereof; FIG. 12 is a right side elevational view thereof; FIG. 13 is a top plan view thereof; and, FIG. 14 is a bottom plan view thereof.

The broken lines in the drawings illustrate portions of the gas valve with integrated pressure regulator that form no part of the claimed ornamental design.
